(57) **CLAIM**

The ornamental design for an electrical power grommet for a work surface, as shown and described.

DESCRIPTION

FIG. 1 is a top, left, front perspective view of an electrical power grommet for a work surface, showing our new design;

FIG. 2 is a top, left, rear perspective view thereof;

FIG. 3 is a bottom, right, front perspective view thereof;

FIG. 4 is a bottom, left, front perspective view thereof;

FIG. 5 is a top plan view thereof;

FIG. 6 is a bottom plan view thereof;

FIG. 7 is a front elevation thereof;

FIG. 8 is a rear elevation thereof;

FIG. 9 is a left side elevation thereof; and,

FIG. 10 is a right side elevation thereof.

In the drawings, the broken lines depict unclaimed subject matter only and form no part of the claimed design.

1 Claim, 5 Drawing Sheets
